UNITED STATES PATENT OFFICE

JOHN J. PICHERTE, OF WHITINSVILLE, MASSACHUSETTS

SPINDLE

Application filed December 7, 1928. Serial No. 324,380.

This invention relates to a spindle on which spinning or twisting operations may be performed.

It is customary to mount a bobbin on a vertical spindle and to rotate the spindle and bobbin at high speed, the driving engagement of the spindle with the bobbin being entirely frictional.

It is the object of my invention to provide an improved form of friction driving connection between the spindle and the bobbin, by which the bobbin will be accurately centered and effectively rotated.

My invention further relates to arrangements and combinations of parts which will be hereinafter described and more particularly pointed out in the appended claims.

A preferred form of the invention is shown in the drawings in which

20 Fig. 1 is a side elevation of parts of a spindle embodying my improvements;

Fig. 2 is a sectional side elevation of the spindle and friction driving connection;

25 Figs. 3 and 4 are front and side elevations respectively of one of the separate driving members, and

Fig. 5 is a detail sectional view taken along the line 5-5 in Fig. 3.

Referring to the drawings, my improved 30 spindle comprises a blade 10 having a whirl 11 fixed thereon, said whirl being formed with an upwardly projecting sleeve portion 12 and with an annular groove 13 formed in the upper surface of the whirl, on which surface the bobbin is supported.

35 A casing member 15 is secured on the blade 10 above the whirl 11 and is provided with a plurality of spaced depending arms 16, separated by downwardly extended slots or 40 openings 17. Bobbin-engaging or friction driving members 20 are mounted in the several openings 17.

Each member 20 is preferably formed from a single piece of sheet metal, struck up or 45 pressed to the section shown in Fig. 5, with a middle bobbin-engaging portion 21 and with side flanges 22. An upward extension 23 of each member 20 is bent rearward and downward as indicated in Figs. 2 and 3.

50 The driving members 20 are preferably

formed of resilient sheet steel and the members 23 constitute spring elements which yieldingly engage the blade 10 and force the members 20 outward, such outward movement being limited by engagement of the side flanges 22 with the inner surfaces of the depending arms 16 of the casing 15.

It will be understood that the driving members 20 are placed within the casing 15 before the casing is assembled with the whirl 11 on the blade 10. The lower ends of the arms 16 and of the driving members 20 are positioned in the groove 13 and are centered thereby.

When a bobbin is placed on the spindle, the inner wall of the bobbin will engage the outwardly projecting members 20, forcing them inward a certain distance against the outward pressure of the springs 23, the members 20 thereby providing a frictional driving engagement with said bobbin.

The driving members 20 are held in spaced relation by the arms 16, and each driving member is a separate and complete unit, preferably having its spring portion 23 formed integral therewith. The entire device is thus 75 extremely simple, while at the same time it is effective and reliable in use.

Having thus described my invention and the advantages thereof, I do not wish to be limited to the details herein disclosed otherwise than as set forth in the claims but what I claim is:—

1. In a spindle, a blade, a whirl, a casing mounted on said blade above said whirl and having a plurality of elongated side openings, and a separate outwardly spring-pressed driving member mounted in each opening and supported on said whirl, each driving member having an inner integral spring portion depending from its upper end portion and yieldingly engaging said blade.

2. In a spindle, a blade, a whirl, a casing mounted on said blade above said whirl and having a plurality of elongated side openings, and a separate outwardly spring-pressed driving member mounted in each opening and supported on said whirl, each driving member being formed of a single piece of thin sheet steel and having an inner spring portion forming an integral projection at one end

of said member and bent to extend reversely alongside said member and to yieldingly engage said spindle blade.

3. In a spindle, a blade, a whirl, a casing mounted on said blade above said whirl and having a plurality of elongated side openings, and a separate outwardly spring-pressed driving member mounted in each opening and supported on said whirl, each driving member being formed of a single piece of thin sheet steel and having an integral inner spring portion engaging said spindle blade and having side portions engaging said casing to limit outward movement of said driving member.

4. In a spindle, a blade, a whirl, a casing mounted on said blade above said whirl and having a plurality of elongated side openings, and a separate outwardly spring-pressed driving member mounted in each opening and supported on said whirl, each driving member being formed of a single piece of thin sheet steel and having an integral inner spring portion engaging said spindle blade and having side portions engaging said casing to limit outward movement of said driving member and having a longitudinal center portion projecting outward through the associated casing opening to engage the inner wall of a bobbin supported on said spindle.

5. In a spindle, a blade, a whirl, a casing mounted on said blade above said whirl and having a plurality of elongated side openings, and a driving member mounted in each of said openings and projecting outward therethrough to engage the inner wall of a bobbin supported on said spindle, each driving member having side portions limiting outward movement thereof and having an upward extension bent rearward and downward to form a spring tongue yieldingly engaging said spindle blade.

In testimony whereof I have hereunto affixed my signature.

JOHN J. PICHERTE.
